UNITED STATES PATENT OFFICE.

MICHAEL J. OWENS, DECEASED, LATE OF TOLEDO, OHIO; BY JOHN H. MCNERNEY,
JAMES C. BLAIR, AND HAZEL O. BEESCH, ADMINISTRATORS, OF TOLEDO, OHIO, AS-
SIGNORS TO THE OWENS BOTTLE COMPANY, OF TOLEDO, OHIO, A CORPORATION OF
OHIO.

APPARATUS FOR GUIDING AND CONVEYING HOT GLASSWARE.

Application filed March 22, 1924. Serial No. 701,056.

The present invention relates to apparatus for receiving bottles or other glass articles as they are discharged from a forming machine and guiding and conveying them away from the machine. The invention is particularly adapted for use with a machine of the type in which a plurality of such articles are simultaneously discharged.

An object of the invention is to provide practical means for receiving and guiding the individual articles separately as they are discharged from the molds and keeping them out of contact with each other until they have cooled sufficiently to prevent them from sticking together or becoming scratched or marred when brought in contact with each other.

In its preferred form, the invention comprises arms carrying funnel guides into which the bottles or other articles are discharged from the molds and through which such articles drop onto a bank of chutes by which they are directed onto a conveyor. A further feature of the invention relates to means by which an operator may readily swing said arms to one side and invert the funnel guides to clear them of any articles that may have become lodged therein.

Other features of the invention will appear hereinafter.

In the accompanying drawings:

Figure 1 is a perspective view of an apparatus constructed in accordance with my invention, and also shows a pair of finishing molds on a bottle blowing machine to which the invention is applied.

Figure 2 is an elevation of the same.

Figure 3 is a part sectional plan view of one of the arms carrying the funnel guides and means for actuating said arm.

Figure 4 is a part sectional elevation of the same.

Figure 5 is a fragmentary elevation view showing a rack and pinion for horizontally adjusting the frame which carries the chutes.

Figure 6 is a section at the line VI—VI on Figure 2.

The invention is herein shown as designed

for use with a bottle blowing machine. The apparatus for receiving the bottles as they are discharged from the molds is supported on a horizontally disposed arm or framework 10 secured to and projecting radially from the stationary frame 11 of the bottle blowing machine. An article receiving and guiding member 13 comprises a bank of chutes 12 formed of sheet metal. The chutes or guideways 12 are arranged side by side and are downwardly and forwardly convergent. The member 13 is secured by bracket arms 14 to a transverse frame member 15. Depending lugs 16 on said frame member carry a transverse rod 17 provided with rolls 18 to run on stationary tracks 19 on the frame 10. The forward end of the member 13 is supported on a track 21 carried on an arm 22 at the forward end of the frame 10. A yoke 23 carrying rolls 24 running on the track 21, has a swivel connection 25 with the member 13.

The frame member 15 is provided at each end with vertical guideways 26 in which rack bars 27 are mounted for vertical adjustment. These rack bars have secured at their lower ends respectively, bearing sleeves 28 and 29, and at their upper ends, gears 31 and 32 (Fig. 1). The gear 31, as shown in Figures 3 and 4, is a mutilated gear formed with bevel gear teeth in mesh with a bevel pinion 33, the shaft 34 of which carries an arm 35 to which are attached a plurality of funnel shaped guides 36. The shaft 34 is journalled in a bearing 37 formed in a gear casing 38 mounted on the gear 31 for horizontal rotation about the axis of said gear. Ball bearings 39 may be interposed between the casing 38 and gear 31. A vertical rock shaft 41 is keyed to the casing 38 and extends downward through the gear 31 and bearing 28. A rock arm 42 is attached to the lower end of the shaft 41 and is connected through a transverse rod 43 to a rock shaft 44 secured to the lower end of a vertical rock shaft 45 which is journalled in the bearing 29 and extends upward through the gear 32 and a gear casing 46.

95

An arm 47 also carrying funnel guides 36 is journaled in the gear casing 46 and carries a gear meshing with the gear 32.

The arms which carry the funnel guides 36 are adjustable vertically by means of a hand crank 48 attached to a shaft 49 journaled in the frame member 15, said shaft carrying pinions 51 running in mesh with the racks 27. By rotating the crank 48, 10 the funnel guides are adjustable vertically toward and from the chutes 12. The battery of chutes 12 together with the funnel guides are adjustable horizontally toward and from the machine frame 11 by means of 15 a hand wheel 52 on a shaft 53 carrying a pinion 54 running in mesh with a rack bar 55 attached to the member 13. This permits the funnel guides to be accurately adjusted forwardly and rearwardly to the proper 20 position to catch the falling bottles. Also, by means of the hand wheel 52 the apparatus can be quickly moved forward out of the path of the bottles when it is not desired to deliver them to the conveyor 57.

25 The bottles 59 are discharged from the finishing molds 61 of the blowing machine. In the type of bottle blowing machine indicated, the molds are arranged in pairs, each pair comprising a plurality of mold 30 cavities. Each pair of molds may be opened simultaneously so that all the bottles are dropped at the same time from the molds. During the opening of the molds, the bottles are temporarily held on the mold bottoms by the usual arms 62 which then 35 release the bottles and allow them to drop neck end first into and through the funnel guides 36. These guides are in register with the chutes so that the bottles drop onto the 40 chutes and slide down them by gravity, neck end first. As they slide off the lower forward ends of the chutes, they drop between the partitions or guide plates 63 (Figs. 1 and 2) onto a belt conveyor 57 which carries 45 them forward to the annealing leir.

If at any time one of the funnel guides becomes clogged as may occur if the bottles accidentally become jammed in the funnel or if a bottle falls crosswise and lodges in 50 the funnel, the latter is cleared by the following means: If, for example, it is desired to clear a funnel or funnels on the arm 35, a handle 64 secured to the upper end of the rock shaft 45 is operated to rock said shaft 55 and through the rod 43 rock the shaft 41. This rotates the gear casing 38 secured to the shaft 41 so that the arm 35 is swung forward about the axis of the shaft 41. During this forward movement of the arm, the pinion 33 thereon running in mesh with the gear 31 rotates said arm about its own horizontal axis so that the guides 36 are inverted as the arm swings forward.

Figure 3 indicates in broken lines, the

guides in their partly inverted position. As 65 the guides are turned upside down, any bottles or articles lodged therein will drop out by gravity. The hand lever 64 (Figs. 1 and 2) is then returned, restoring the parts to normal position. The funnel guides on 70 the arm 47 are in like manner cleared by operating a hand lever 65 attached directly to the gear casing 46, thereby swinging said arm forward and inverting it in the same manner as above described in connection with 75 the arm 35.

Modifications may be resorted to within the spirit and scope of the invention.

What is claimed is:

1. In an apparatus for handling glass 80 articles, the combination of a plurality of funnel shaped guides upwardly and outwardly flared to receive articles dropped therein, means for simultaneously dropping a plurality of bottles or similar articles neck 85 end downward and causing them to pass by a continuous movement into, through and beyond the guides from a position over the guides, the articles being distributed singly 90 to the respective guides, and a plurality of downwardly convergent inclined chutes arranged with their upper receiving ends directly beneath the said guides in position to permit said articles to drop from the 95 guides directly into the chutes. 55

2. The combination of a plurality of inclined chutes, funnel shaped guides individual to and arranged directly over the upper portions of the chutes, said guides having upwardly and outwardly flared upper 100 ends for receiving articles and forming enclosed passageways through which the articles drop, said guides arranged to guide the articles directly onto the chutes and having normally a fixed relation to the chutes, and means for moving the guides as a group 105 out of operative relation to the chutes. 105

3. The combination of a glass forming machine comprising molds from which a 110 plurality of bottles or like articles are concomitantly delivered, a series of inclined chutes individual to said articles and arranged to receive the articles when they are delivered from the molds, and funnel guides individual to the chutes, arranged between the molds and the chutes for directing the articles individually to the chutes, said guides being upwardly and outwardly flared to provide wide mouths for receiving the articles, said guides forming enclosed channels through which the articles pass by a continuous movement from the molds to the chutes, said guides having their lower ends directly over and in proximity to the chutes 115 and arranged to guide the articles directly from the guides onto the chutes. 120

4. The combination of a glass forming machine comprising molds from which a 125

plurality of bottles or like articles are comitantly delivered, a series of inclined chutes individual to said articles and arranged to receive the articles when they are delivered from the molds, funnel guides individual to the chutes, arranged between the molds and the chutes for directing the articles individually to the chutes, said guides being upwardly and outwardly flared to provide wide mouths for receiving the articles, said guides forming enclosed channels through which the articles pass and having their lower ends directly over and in proximity to the chutes and arranged to guide the articles directly from the guides onto the chutes, and means for inverting the guides to dislodge articles therefrom.

5. The combination of a mold, receiving means for articles discharged from the mold, a guide in position to receive an article discharged from the mold and guide it to said receiving means while the guide is in said receiving position, and means for actuating said guide to dislodge an article therefrom if the latter becomes lodged in the guide and discharge it away from said receiving means.

6. The combination of a mold, a guide in position to receive and guide an article discharged from the mold, and manually operated means for inverting said guide to dislodge an article therefrom.

7. The combination of a funnel shaped guide, means for directing articles to and through said guide, and a manual device for inverting said guide to dislodge an article therefrom.

8. The combination of a funnel shaped guide, means for directing articles to and through said guide, and manual means to swing said guide to one side of its normal position and invert it to dislodge an article or articles therefrom.

9. The combination of a funnel shaped guide, means for directing articles to and through said guide, an arm on which the guide is carried, and means to swing said arm about a horizontal axis and simultaneously invert the guide.

10. The combination of a horizontally disposed arm, funnel guides arranged at intervals along said arm, means to swing the arm about a horizontal axis, and means to rotate the arm about its own axis to invert the guides.

11. The combination of a horizontally disposed arm, a guide carried thereby, a pinion mounted on said arm, a stationary gear having a vertical axis, said gear being in mesh with said pinion, and means to swing the arm about said vertical axis and cause the pinion to simultaneously rotate the arm about its own axis to invert the guide.

12. Apparatus for handling bottles and

the like comprising horizontally disposed arms arranged substantially in alignment, guides on said arms, means for delivering articles to said guides, and manual devices comprising handles individual to said arms for selectively actuating the arms to invert the guides and thereby dislodge articles therefrom, said handles being arranged adjacent to each other at the same side of the apparatus in position to permit an operator to selectively actuate the arms without shifting his position.

13. The combination of a horizontally disposed frame, horizontal arms supported respectively at opposite ends of the frame, each arm projecting inwardly from its support toward the other arm, guides carried on the arms, and mechanism for individually swinging said arms about vertical axes at the ends of said frame and simultaneously rotating the arm about its horizontal axis to invert the guides thereon, said means comprising manual devices at the same side of the frame whereby the arms may be selectively actuated by an operator from one position.

14. The combination of a horizontally disposed frame, horizontal arms supported respectively at opposite ends of the frame, each arm projecting inwardly from its support toward the other arm, guides carried on the arms, and mechanism for individually swinging said arms about vertical axes at the ends of said frame and simultaneously rotating the arm about its horizontal axis to invert the guides thereon.

15. The combination of a glass forming machine comprising molds having plural mold cavities, a series of funnel guides arranged to receive the articles discharged from the molds, said guides being arranged side by side, a series of chutes individual to the said guides, said chutes being arranged beneath the guides, and manual means to swing the guides to a position at one side of the chutes and invert the guides to dislodge articles therefrom.

16. The combination of a glass forming machine comprising molds from which articles are discharged, apparatus for receiving said articles comprising a battery of inclined chutes arranged side by side with their upper ends beneath the points of discharge of said articles from the molds, means interposed between the molds and chutes for guiding the articles into the chutes, said means comprising funnel guides through which the articles are guided endwise to the chutes, and manual means for shifting the guides out of range of the chutes and inverting them to dislodge articles therefrom.

17. The combination of a glass forming machine comprising molds from which articles are discharged, apparatus for receiving

said articles comprising a battery of inclined chutes arranged side by side with their upper ends beneath the points of discharge of said articles from the molds, means interposed between the molds and chutes for guiding the articles into the chutes, means for adjusting said chutes up and down, and means for adjusting the chutes and guides in a horizontal direction.

Signed at Toledo, in the county of Lucas ¹⁰ and State of Ohio, this 11th day of March, 1924.
